UNITED STATES PATENT OFFICE.

MICHAEL CAVANAGH, OF NEW YORK, N. Y.

GAGE FOR SKIVING-MACHINES.

No. 876,772.

Specification of Letters Patent.

Patented Jan. 14, 1908.

Application filed August 7, 1907. Serial No. 387,398.

To all whom it may concern:

Be it known that I, MICHAEL CAVANAGH, a citizen of the United States, residing in New York, in the borough of Brooklyn, county of 5 Kings, and State of New York, have invented certain new and useful Improvements in Gages for Skiving-Machines, of which the following is a specification.

This invention relates to gages for skiving machines, and more particularly to gages such as are used in connection with machines of this character in which a grooved feed-roll co-acts with a rotary table in order to feed the counters to the cutting-knife.

15 In machines of this character as at present constructed there is usually employed a gage to regulate the cutting action of the knife and such gage is usually mounted upon a fixed part of the machine in such a manner 20 as to slightly overlie the feed-table, which is mounted to rotate in a horizontal plane. The gage as usually constructed consists of a block secured to said fixed part and extending parallel with the plane of rotation of the 25 feed-roll and approximately tangential to the feed-table in such a manner as to properly guide the counter between the feed-roll and table.

It has been found in practice that by the 30 contact of the counters with the gage the latter is quickly worn away. In this manner the gage becomes useless and has to be often entirely replaced.

The object of this invention is to avoid 35 this defect and provide a gage which embodies an adjustable wearing surface, whereby the life of the gage is greatly increased.

With this end in view, the invention consists in a gage for the purpose indicated, 40 which comprises a wearing plate of extremely hard metal which is clamped to the machine by a clamping block in such a manner as to be reversible, as will appear from the following description and claims.

45 In the accompanying drawings, in which the same reference characters denote corresponding parts throughout, Figure 1 is a perspective view of a skiving machine having a gage constructed in accordance with this invention applied thereto. Fig. 2 is an enlarged perspective view of the gage, and Fig. 50 3 is a vertical longitudinal section of the gage showing the same clamped to the machine.

55 Referring to the drawings, the horizontal feed-table 5 of the machine is supported and rotatable in a standard 5^x, and coöperating

with said table is the grooved feed-roll 6. The cutting-knife 7 is located behind the feed-roll, and to the fixed part 8 of the machine, at one side of the feed-table, the gage 60 is applied. All of these parts are of known construction.

The invention consists in providing a gage which is made in two parts: an oblong wear-resisting plate 9, and a clamping block 10. 65 The plate 9 forms the base of the gage and projects at either end beyond the block 10. Said plate is preferably made of very hard steel, though any other very hard wear-resisting metal might be used. The clamping 70 block 10 may be made of any suitable material, preferably inferior metal and of a cheaper quality.

The gage is applied to the fixed part 8 of the machine in such a manner that one end 75 of the wearing plate 9 extends into coöperative relation with the feed-roll. It is clamped in position by the block 10, which is superposed thereon. Screws 11 pass downwardly through said block and the wearing plate 80 into the fixed part 8, as shown in Fig. 3. In this position of the wearing plate, its forward end will come in contact with the rapidly rotated counters, which being simultaneously cut, are swung with considerable 85 force against the gage. This will cause a wearing away of the plate at the end of one side.

Hitherto, a new gage would soon be so worn away as to be absolutely useless, so that 90 a continued cost in the operation of the machine was occasioned. In my improved gage, when one end of the plate becomes worn, the wearing plate is separated from the block 10 and reversed horizontally, that is to say, so 95 that the end which was directed away from the table is now directed towards it. When this end also becomes worn away, the wearing plate is again separated from the block 10 and is turned over, whereby new side-ends 100 may be now subjected to the wearing action. Thus it will be seen that four different parts of the wearing plate may be presented to the counters, whereby the life of the gage may be correspondingly increased as compared to 105 those in which no replaceable wearing surface is provided. The adjustment of the wearing plate can always be readily effected as it is only necessary to remove the screws 11 and then replace the same after the wearing plate has been turned. When one of the 110 wearing plates is worn out, it can be replaced

at little expense by a new one which is clamped in position by the same devices, the block 10 being used throughout for the different plates.

5 Having thus described my invention, I claim as new and desire to secure by Letters Patent:

1. A gage for skiving machines, comprising a rectangular wearing plate of wear-resisting material, and a superposed clamping block beyond which said plate extends at both ends and which is detachable in order to permit the reversal of said plate so that different sides thereof may be brought into 15 action.

2. In a skiving machine, the combination, with the feed-table rotatable in a horizontal plane and the fixed part at the side of said table, of a gage comprising a reversible rectangular wearing plate extending tangentially to said feed-table, and a clamping block superposed on said wearing plate by which the latter is clamped to said fixed part. 20

In testimony, that I claim the foregoing as my invention, I have signed my name in presence of two subscribing witnesses.

MICHAEL CAVANAGH.
